[57] CLAIM

The ornamental design for a horizontally perforated half-circle window covering, as shown and described.

DESCRIPTION

FIG. 1 is a front elevational view of a horizontally perforated half-circle window covering showing my new design;
FIG. 2 is a rear elevational view thereof;
FIG. 3 is a left side elevational view thereof, the right side being a mirror image thereof;
FIG. 4 is a top plan view thereof;
FIG. 5 is a front perspective view thereof; and,
FIG. 6 is a rear perspective view.
